[57] CLAIM

The ornamental design for a bait casting rod handle, as shown and described.

DESCRIPTION

FIG. 1 is a left side elevational view of a bait casting rod handle showing our new design, the right side elevational view being substantially a mirror image thereof;

FIG. 2 is a top plan view thereof;

FIG. 3 is a bottom plan view thereof;

FIG. 4 is a front elevational view thereof; and

FIG. 5 is a rear elevational view thereof.
